FIG. 1

FIG. 2

INVENTOR
LEONARD AKER

BY

Philip G. Minnis.

UNITED STATES PATENT OFFICE

134,126

DESIGN FOR A FIRE TRUCK BODY

Leonard Aker, Atherton, Calif., assignor to Food
Machinery Corporation, San Jose, Calif., a cor-
poration of Delaware

Application March 16, 1942, Serial No. 106,205

Term of patent 14 years

To all whom it may concern:

Be it known that I, Leonard Aker, a citizen of the United States and a resident of Atherton, county of San Mateo, State of California, have invented a new, original, and ornamental Design for a Fire Truck Body, of which the following is a specification, reference being had to the accompanying drawing, forming part thereof.

Fig. 1 is a perspective view of a fire truck body

embodying my new design, the view being taken from the front thereof.

Fig. 2 is a perspective view of the fire truck body shown in Fig. 1, the view being taken from the rear thereof.

I claim:

The ornamental design for a fire truck body, as shown.

LEONARD AKER.
